UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

GUARD PLATE AND GUARD PLATE SUPPORT FOR SLICING MACHINES

Application filed July 12, 1929. Serial No. 377,842.

My invention relates to a slicing machine of the type in which a rotary knife is employed, together with means for conveying the work to be sliced across the face and past the cutting edge of said knife. One object of my invention is to provide an improved mounting for the guard plate for the forward face of said knife. Another object is the provision of means for mounting or protecting the drive for said knife. Other objects will appear from time to time in the course of the specification and claims.

I illustrate my invention more or less diagrammatically in the accompanying drawings, wherein—

Figure 1 is a front elevation;

Figure 2 is a section on the line 2—2 of Figure 1;

Figure 3 is a section on the line 3—3 of Figure 1;

Figure 4 is a section on the line 4—4 of Figure 1; and

Figure 5 is a detail.

Like parts are indicated by like symbols throughout the specification and drawings.

A generally indicates a base member mounted for example upon the ground engaging supports A¹. Mounted on the base in any suitable manner is a motor B with its shaft B¹ and drive pulley B².

C is a frame or partition member upwardly projecting from the base A and apertured as at C¹ to permit the passage therethrough of the motor shaft B¹. C³ indicates any suitable housing member for the motor. C⁴ is a flange, forwardly projecting from the partition C, which serves as a partial enclosure of the drive for the knife. C⁵ indicates a bearing portion herein shown as integral with the frame and continuous with the partition C. It is provided with a forwardly projecting guard member C⁶.

D indicates a knife shaft, rotatable in the portion C⁵ and provided with a pulley D¹ about which passes the belt D², whereby the pulley D¹ is driven from the motor pulley B². D³ indicates the knife recessed in its forward face as at D⁴ and on its rear face as at D⁵. The guard portion C⁶ penetrates the rear recess, as shown for example in Figure 2.

E indicates a guard plate for the forward face of the knife. Its arcuate edge E¹ penetrates the recess D⁴ at the front of the knife. It will be seen, as in Figure 2, that the knife axis is somewhat inclined, in order to throw the cutting arc of the knife forwardly into the plane of the guard plate E. E² indicates a supporting plate which slidably seats in the recesses E³ E⁴ of the frame, as shown for example in Figures 3 and 4. This member E² is shown in detail in Figure 5 its upper edge E⁵ seating in the slot E⁴ and its lower edge E⁶ seating in the slot E³. It is arcuately cut away as at E⁷, this cut away portion, indicated in dotted line in Figure 1, being masked by the knife when the assembly is in operative position. The plate E is movable as a unit with the plate E² and is adjustably supported thereon. As an example of such adjustment I illustrate, as in Figure 4, the screwthreaded pin E⁸, on the plate E², with the abutment nut E⁹ and the spacing nut E¹⁰. Screwthreaded for engagement with the spacing nut is the securing screw E¹¹, with its external washer E¹², which penetrates the nut E¹⁰, as shown in Figure 4. The guard plate E is thereby held in relation to the plate E² at the desired adjustment. E¹³ indicates a securing member or screw, adjacent the slot E⁴, whereby the plate E² may be held against movement when set in position.

G indicates a cover which is held in position on the frame, as by the securing member G¹. It is provided with a circumferential depending apron G². G³ is an end or side cover plate, which may be held in position as by the securing screws G⁴.

H indicates a scraper opposed to the forward face of the knife, as shown for example in Figure 1. Preferably it is adjustably mounted as for example by the ball and socket or universal connection including the ball H¹, the cup member H², and the securing screw H³.

J indicates a work supporting carriage, with the work engaging surface J¹ mounted thereon. The carriage is movable for example along the tracks J² J³, whereby the work may be guided across the face of the knife.

K indicates any desired gauge plate structure which may be moved away from the cutting plane in order to vary the thickness of the slices cut.

5 When the closure plate G³ is in position it prevents movement of the plate E². I may provide the additional locking means, as for example the screw E¹³.

It will be realized that whereas I have described and shown a practical and operative device, nevertheless many changes might be made in the size, shape, number and disposition of parts without departing from the spirit of my invention. I therefore wish my 10 description and drawings to be taken as in a broad sense illustrative and diagrammatic rather than as limiting me to my specific showing. The use and operation of my invention are as follows:

20 It is frequently important to remove the guard plate E, for access to the knife and knife drive. It is also important, however, that the adjustment of such guard plate E, in relation to the knife, be not disturbed. I 25 therefore provide the plate E² which serves as a support for the plate E and which is fixed, as to its position in relation to the frame, by its engagement with the slots E³ E⁴. When it is desired to remove the guard plate E the 30 cover G may be removed, and the end plate G³. The operator may then loosen the set screw E¹³ if such is employed for holding means and withdraw the plate E², and with it the guard plate E, without disturbing the 35 adjustment of the guard plate.

The guard structure so provided is important, in the type of knife herein disclosed, because the rapid rotation of a motor driven knife tends to carry dirt, grease, bits of meat 40 and the like into the space to the rear of the guard plate E. Both in the interest of sanitation and for the protection of the drive, which may include a rubber belt I desire to limit to a minimum the access of such material and also to make the removal of such 45 material and the interior cleaning of the device easy. When the assembly is in the position in which it is shown, for example, in Figure 2, the guard plate entirely protects 50 the face of the knife except for the peripheral strip about the relatively restricted cutting edge. The material which adheres to the front of the knife is largely removed by the scraper H. Whatever material does penetrate the space to the rear of the plate E can 55 go no farther because the plate E² penetrates within the periphery of the knife and the material delivered by the knife will inevitably be delivered centrifugally outwardly 60 away from the knife axis. The plate E therefore completes the closure of what is a substantially closed chamber for the transmission. Since the belt D² may be made of rubber, it is particularly important that it be 65 not contacted by grease, meat juices, lard and

the like and the structure herein shown provides a particularly efficient means for protecting the said belt.

I claim:

1. In a slicing machine, a rotary knife, 70 means for rotating it, and a driving connection between said rotating means and said knife, a frame including a portion extending upwardly about said knife, a guard plate positioned forwardly of said knife, a supporting plate forming with the guard plate a structure removable as a unit, said supporting plate including a portion adapted to be interposed between the rear face of the knife and the said driving connection. 75

2. In a slicing machine, a rotary knife, means for rotating it, and a driving connection between said rotating means and said knife, a frame including a portion extending upwardly about said knife, a guard plate positioned forwardly of said knife, a supporting plate forming with the guard plate a structure removable as a unit, said supporting plate including a portion adapted to be interposed between the rear face of the knife 80 and the said driving connection, the supporting plate being slidably mounted in the frame. 85

3. In a slicing machine which includes a rotary knife and means for rotating it, a 90 frame on which said knife is mounted, said frame including a portion extending upwardly about said knife, a guard plate positioned forwardly of said knife, and a supporting plate for said plate, said supporting plate and guard plate being unitarily removable from the frame, the supporting plate being slidably mounted in the frame and removable longitudinally from one end thereof and an additional closure plate for 95 the end of the frame and means for securing it in position, said closure plate being adapted, when so secured, to hold the supporting plate against movement in relation to the frame. 100

4. In a slicing machine which includes a rotary knife and means for rotating it, a frame on which said knife is mounted, said frame including a portion extending upwardly about said knife, a guard plate positioned forwardly of said knife, and a support for said guard plate, said support and guard plate being unitarily removable from the frame, and a closure plate for the frame, and means for securing it in position, said closure plate being adapted, when so secured, 105 to hold the support against movement in relation to the frame. 110

5. In a slicing machine, a motor, a rotary knife, a driving connection between knife 115 and motor, a removable guard plate for the forward face of the knife, and a supporting plate for said guard plate, said supporting plate being interposed between the knife and the driving connection. 120

6. In a slicing machine a motor, a knife, a driving connection between knife and motor, a frame on which said knife is mounted, said frame including a portion extending
5 upwardly about said knife and adapted to mask one face of the knife, a guard plate positioned forwardly of said knife and adapted to mask the opposite face of the knife, and a supporting plate for said guard plate, said supporting plate being positioned to the rear of said knife and between said knife and said driving connection, and extending substantially within the periphery of the knife.
- 15 7. The structure of claim 6 characterized in that said supporting plate is slidably mounted for sliding movement in a plane generally parallel with the plane of the knife.
- 20 Signed at Indianapolis, county of Marion, and State of Indiana, this 25th day of June, 1929.

WILLIAM J. CAMPBELL.
